UNITED STATES PATENT OFFICE.

WILLIAM GATKE, OF PORTLAND, OREGON.

WOOD-PULP-FORMING MACHINE.

1,215,516.

Specification of Letters Patent. Patented Feb. 13, 1917.

Application filed March 16, 1916. Serial No. 84,556.

To all whom it may concern:

Be it known that I, WILLIAM GATKE, a citizen of the United States, residing at Portland, in the county of Multnomah and State of Oregon, have invented a new and useful Wood-Pulp-Forming Machine to Form and Dry Various Articles of Different Shapes and Sizes Made from Wood-Pulp, of which the following is a specification.

10 This invention relates to machines for forming articles from wood pulp, and its object is to provide a simple and efficient machine of this kind.

15 The object stated is attained by means of a novel combination and arrangement of parts to be hereinafter described and claimed, and in order that the same may be better understood, reference is had to the accompanying drawings forming a part of this

20 specification.

In the drawings, Figure 1 is a side elevation of the machine, partly broken away; Fig. 2 is a cross-section of one of the male and female former units in co-operative position; Fig. 3 is a plan view of a fragment of one of the male former units; Fig. 4 is a longitudinal section of one of the female former units with a male former unit in co-operative relation therewith; Fig. 5 is a cross section of the drying oven and one of the female formers therein; Fig. 6 is a longitudinal section of a fragment of the oven, and Fig. 7 is a plan view of a fragment of one of the female former units.

25 Referring specifically to the drawings, the frame of the machine comprises standards 10 having suitable braces and connections. At one end of the frame is mounted a bearing 11 for the shaft 12 of a forming wheel, 30 said shaft being also provided with a drive pulley 13 connected by a belt 14 to a suitable power source. The forming wheel consists of a rim 15, a hub 16 and spokes 17. On the periphery of the rim are mounted the male formers which operate in conjunction with female formers or molds, which latter are connected in a manner to form an endless belt, the same being trained to travel partly around in forming wheel to bring the two 35 sets of formers in co-operative relation, as will be presently described. The drawings show one forming wheel and one belt of molds, but these parts may be duplicated if a twin machine is desired, which can be 40 readily done by mounting two forming

wheels on the shaft 12, with the pulley 13 therebetween, and providing a mold belt for each of said wheels. The capacity of the machine can be further increased by increasing the number of forming elements. 45

The male formers are composed of a series of units mounted on the periphery of the rim 15, each unit comprising a hollow body 18 having outstanding hollow protuberances 19, the latter being shaped to correspond to the shape of the articles to be molded. The parts 19 have perforations 20, and in the ends of the body 18 are drain openings 21. These units are secured on the periphery of the rim 15 by screws 22, or any 50 other suitable means, and they extend entirely around the rim.

The female formers or molds are composed of a series of units, each of which comprises a body 23 having one of its sides 55 shaped to conform to the male formers, said side having a series of mold cavities 24 shaped and dimensioned to permit the formers 19 to enter the same. From the side edges of the body 23, at the ends thereof, extend pins 25 for the attachment of links 26 which connect the units in the form of an endless belt or chain. The body 23 has a raised rim 27 to hold the charge of pulp in the cavities 24. When one of the units 18 comes opposite a unit 23, the parts 19 enter the cavities 24 and shape the pulp in the latter, and the base portion of the unit 18 comes inside the rim 27, and by its engagement therewith propels the endless belt of molds 60 forward, and also properly centers the parts 19 in the cavities 24. The belt is therefore not fed forward by the parts 19 entering the cavities 24, but is propelled solely by the engagement of the base portions of the units 18 with the rim 27, the action being in all respects similar to a sprocket-and-chain gearing. The rim 27 also has an internal shoulder 28, and the unit 18 has an external shoulder 29 at its base. These shoulders are 65 opposite each other when the two units are in co-operative relation, and they limit the extent to which the protuberances 19 enter the cavities 24. During the molding operation, the water is pressed out of the pulp and escapes by the way of the perforations 20 and the drain openings 21.

The endless belt or chain of molds hereinbefore described passes over three idler pulleys 30, and also over guide rollers 31 car- 70

ried by the frame 10, and so positioned and arranged that the upper run of the belt is held close enough to the periphery of the rim 13 to bring the male formers and the molds in proper coöperative relation. The upper run of the belt, where it leads from the forming wheel, is held horizontally by the guide rollers here, and this portion of the belt passes through a drying oven to dry 10 the shaped pulp in the mold cavities 24.

The drying oven is an inclosure carried by the frame 10 of the machine, and composed of a top 32, a bottom 33 and sides 34, the inclosure being open at its ends to allow 15 the belt of molds to pass therethrough. Gas burner pipes 35 extend across the oven, above and below the belt, they being suitably connected to a supply pipe 36. It will be understood of course, that any other 20 means may be provided for heating the oven, or for applying heat to the belt of molds as it passes through the inclosure.

The pulp is fed to the belt of molds through a spout 37 which discharges on 25 the upper run of the belt adjacent to the point where it comes into coöperative relation with the former wheel.

Upon passing through the oven, the shaped articles are thoroughly dried, and 30 when the belt of molds passes over the idler pulley 30 to the rear of the oven, the mold units are tilted, whereupon the finished articles drop out of the mold cavities, to be taken up by a conveyer or other suitable 35 device, which latter has not been illustrated as it forms no part of the present invention.

The preferred embodiment of the invention has been shown, but it will be understood that various changes and modifications may be made without departure from the spirit or scope of the invention as claimed hereinafter. The apparatus is adapted for 40 molding articles of various shapes by providing corresponding mold and former units.

I claim:

1. A molding apparatus comprising a series of mold units, and a series of former 50 units coöperating therewith and shaped to enter the cavities of the molds, one of said series being connected to form an endless belt, a rotatable element on the periphery of which the other series of units is mounted, and means for guiding the belt past the rotatable element in coöperative relation therewith.

2. A molding apparatus comprising a series of mold units, and a series of former 55 units coöperating therewith and shaped to enter the cavities of the molds, one of said series being connected to form an endless belt, a rotatable element on the periphery of which the other series of units is mounted, and means for guiding the belt past the rotatable 60 element.

element in coöperative relation therewith, driving means for said element, and coöperating means on the units of the respective series for driving the belt from the rotatable element.

3. A molding apparatus comprising a series of mold units, and a series of former units coöperating therewith and shaped to enter the mold cavities, one of said series being connected to form an endless belt, a 70 rotatable element on the periphery of which the other series of units is mounted, means for guiding the belt past the rotatable element in coöperative relation therewith, and a drying oven through which the belt passes 75 after leaving the rotatable element.

4. A molding apparatus comprising a series of mold units, and a series of former units coöperating therewith and shaped to enter the mold cavities, one of said series being connected to form an endless belt, a 80 rotatable element on the periphery of which the other series of units is mounted, means for guiding the belt past the rotatable element, and a drying oven through which the belt passes 85 after leaving the rotatable element, said oven being an inclosure open at its ends for the ingress and egress of the belt, and spaced heating elements in the inclosure between which elements the belt 90 passes.

5. A molding apparatus comprising a series of mold units, and a series of former units coöperating therewith, the mold units being connected to form an endless belt and 100 each mold unit having a series of cavities provided with a raised rim, a rotatable element on the periphery of which the former units are mounted, each of said former units having a series of protuberances shaped to 105 enter the mold cavities and provided with a base portion engageable with the mold units inside the rims thereof for driving the belt, and means for guiding the belt past the rotatable element in coöperative relation 110 therewith.

6. A molding apparatus comprising a series of mold units, and a series of former units coöperating therewith, the mold units being connected to form an endless belt and 115 each mold unit having a series of cavities provided with a raised rim, a rotatable element on the periphery of which the former units are mounted, each of the former units having a series of protuberances shaped to enter the mold cavities and provided with a base portion engageable with the mold units inside the rims thereof for driving the belt, said rims having an internal shoulder and the base portions of the former units 120 having shoulders which are opposite the shoulders of the rim and coöperate therewith to limit the extent to which the protuberances enter the mold cavities.

7. A molding apparatus comprising a 125

series of mold units, and a series of former units coöperating therewith, one of said series being connected to form an endless belt, a rotatable element on the periphery of which the other series of units is mounted, each of said last-mentioned units comprising a hollow body provided with drain open-

ings and having hollow protuberances which are perforated and shaped to enter the mold cavities, and means for guiding the belt past 10 the rotatable element in coöperative relation therewith.

WILLIAM GATKE.
